DEVICE FOR REGISTERING PHYSICAL
CHANGES IN SYSTEMS

Herbert Kienzle, Villingen, Germany

Application October 16, 1937, Serial No. 169,347
In Germany January 25, 1937

5 Claims. (Cl. 235—92)

The present invention relates to a registering device for registering the amount of alteration, from a given physical state, of an apparatus or system, and wherein the steps of alteration are automatically added together, increment by increment, as such changes or alterations occur.

This is accomplished by the operation of a counting device and which is coupled to a variably moving electric instrument, the movements of which are controlled by energy changes in an operative system to which the present device may be adaptably applied.

The present device permits of an arrangement whereby cumulated increments of a predetermined value, and, in some instances, in electrical application, increments of the same sign may be registered progressively, or a series of increments of the opposite sign may be registered.

Any static physical state is invariably subjected to change and a numerical, or registered value is important, for computing the value of such change, or changes because such changes, as produced, are indicative of changes in energy, or stress, and in many instances, indicate energy losses and strains. Registrings of such changes enable one to compute the expenditure of energy output, or the strains to which movable elements of a mechanism may be subjected.

The present device may be utilized, for one purpose, in registering the fluctuations of current flow in electric light circuits, wherein, from time to time the voltages fluctuate greatly in excess of normal, and thereby tend to shorten the life of the lamps. The present device, in registering such fluctuations enables the user to ascertain the amount of fluctuation, and to then correct the fault, thus increasing the effective life of the lamps in use.

In other uses, elements at rest are sometimes subjected to excessive starting strains, and these may be ascertained by the present device, and thereafter analyzed and corrected.

The foregoing and other features of advantage will be apprehended as the herein description proceeds and it is obvious that modifications may be made in the device herein described, without departing from the spirit thereof or the scope of the pending claims.

In the drawing herewith, all of which are more or less diagrammatic, Fig. 1 is a fragmentary view, in elevation, of the essential features of the present improvement; Fig. 2 is a side view of Fig. 1, looking from the right hand side thereof; Fig. 3 is a transverse sectional view of a modified form of actuating device, in the form of an electro-

dynamometer; Figs. 4 and 5, respectively, are enlarged plan and sectional views of the fixed coil of Fig. 3; and Fig. 6 is a diagrammatic illustration of a graph of stress changes.

The device shown in Figs. 1 and 2 is of the moving coil instrument type, and comprises a permanent magnet M, fragmentarily shown, having pole piece extensions N and S, between which latter is pivotally mounted a movable coil W. The coil W, Fig. 2, is fixedly mounted on a shaft 3, the ends of which are rotatably mounted in bearings $h-h$ on supports A—A, located on base B. One of the bearings has an upright extension E, to which the outer end of a spiral tension spring 4 is attached, the inner end thereof being attached to said shaft 3. The opposite bearing A has a plug support 12 thereon, to the inner end of which is attached a spiral spring 5, the inner end of which spring is attached to the shaft 3. Springs 4 and 5 are mounted on shaft 3 with their spirals in opposite directions thereby to balance one another, when adjusted to resiliently hold the coil W in the normal non-operative, rest position as shown in Fig. 1. Each outer terminal end of the springs 4 and 5 are connected to plugs 10 and 12, these being insulated from the arms E and A by insulating bushings 11 and 13. Electrical conducting wires 7 and 7' are connected to said plugs 10 and 12 and thus supply current through the springs 4 and 5 to the windings on coil W, by means not shown. Current from a lamp circuit connected to wires 7 and 7', as changes in voltage occur therein, cause the coil W to vary its position from that shown in full lines in Fig. 1, to the dotted position indicated at X, in the same figure.

The outer end of the shaft 3, as viewed at the left hand side of Fig. 2, fixedly mounts a sector arm 3, the outer end thereof terminating in a toothed gear sector S, which in turn meshes with a toothed gear disc G, which is loosely mounted on the end of the shaft 2 of a counting device C, by its hub H, Fig. 2. The shaft 2 is rotatably supported at its ends by bearings $g-g$ which form the extremities of arms E' and E' which depend from base B.

The shaft is connected to a known counting or adding mechanism, the details not being shown, but indicated at C, in a well known manner.

The geared end of shaft 2, Fig. 2, is provided with a fixed ratchet toothed wheel R, the teeth of which are normally engaged by a spring held ratchet pawl mechanism 18—P both of which are normally mounted upon the outer face of gear G. As thus constructed, when the coil armature W swings on its axis, in the direction of the arrow 55

20, under current changes, it moves the sector S, and this in turn moves the gear G, causing the pawl P to move the ratchet wheel to rotate the adder shaft 2 and thus add the impulse to the 5 counting mechanism as a unit. Upon return of the armature to normal position the ratchet mechanism permits of the return of the gear G, without disturbing or moving adder shaft 2.

In Fig. 3 there is shown an equivalent register 10 actuating structure of alternate construction. This comprises a base portion 16, upon which is mounted a fixed coil magnet 17, which is normally connected into a constant current circuit, and pivotally supports a smaller movable armature 15 coil W', which is provided at its axis ends with spiral control springs, one of which, 4', is shown in Fig. 3. The armature coil W' may be connected into an electric light circuit, as described for Fig. 1, and the coil W' may have an equivalent 20 arm and gear sector S attached thereto, which latter, in turn operates a gear and ratchet movement G, P and R, which operate on an adding shaft 2, as described for Figs. 1 and 2.

The coils herein described may be made as 25 shown in Figs. 4 and 5 wherein a circular frame 17 has two parallel flanges 15-15 joined by an inner, circumferential wall 21. The space between the flanges and wall are wound with a suitable conductive wiring 14. This form of coil is 30 well known.

Fig. 6 is a graphic representation of the function of the present device. Some physical state such as the voltage is shown in function of the time t . The voltage is to be kept at a desired 35 constant value represented by the ordinate V_n . This condition, however, cannot be maintained and the voltage will be subject to variation of 40 more or less degree. During the interval $ta-tb$ the voltage rises to a value V_2 , this rise being equivalent to a certain amount of small increments or subdivisions of voltage unit as shown in the graph. After a time the voltage falls to the 45 normal value V_n and, further, down to the value V_3 . After reaching this value it again rises by a certain amount, equivalent to the number of 50 abscissas as shown. If the construction of the device is arranged that a change of voltage equivalent to one abscissa shown, effects a forward movement of one tooth of the ratchet wheel 55 R, and for this movement the counter C moves forward one unit, then the number of units shown upon the counter will correspond to the amount of change intervals in one direction as shown by the abscissas. If, therefore, the voltage has substantially changed within a certain 60 interval, this condition will be registered by the counter with an equivalent figure. If the voltage has remained quite constant at the value V_n , only the rise of voltage from zero to the value V_n will be registered by the counter with a figure 65 corresponding to the number of abscissas as shown in the graph. Alternatively, the above noted arrangement is not limited to the conditions of one increment movement of the ratchet 70 wheel R, by one tooth. The construction of the device may be so arranged that one tooth is moved forward by 10 abscissas or increments, or any other suitable number. The length of the ordinates V_0-b and $d-e$ above and below the normal value V_n represent by a scale, the amount of change of physical state and for this amount of change the counting device gives a corresponding numerical value to said scale.

What is claimed is:

1. A registering device comprising an electrical instrument adapted to receive current at widely varying large and small rates and having an oscillatory member influenced by said current to deflect from normal widely varying large and 5 small angular distances which are functions of said rate; a gear sector carried and oscillated by said member coaxial with its axis of oscillation; a pinion operated by said sector; a counter having an operating ratchet coaxial with said pinion 10 and having teeth disposed apart angular distances as small as the smallest of the first named distances to be registered; and a pawl carried by said pinion and engaging said ratchet, to operate said ratchet in one direction only by movement 15 of said member in one direction only.

2. In combination, an electric instrument comprising a stator coil, a movable coil oscillatory on an axis diametric to the stator coil, and disposable perpendicular to the plane of the stator coil and movable toward said plane, said coils being adapted to receive current therethrough; one of said coils being adapted to receive current at widely varying rates thereby to deflect the movable coil, from normal, widely varying angular 25 distances which are functions of said rates; a registering mechanism; and means influenced by the movable coil each time it moves in one direction only to cause said mechanism to register 30 an amount which is a function of the angular distance of such movement.

3. In combination, an electric instrument comprising a stator coil, a movable coil oscillatory on an axis diametric to the stator coil, and disposable perpendicular to the plane of the stator coil 35 and movable toward said plane, said coils being adapted to receive current therethrough; one of said coils being adapted to receive current at widely varying rates thereby to deflect the movable coil from normal, widely varying angular 40 distances which are functions of said rates; a rotary element operatively connected to the movable coil and operated by said movable coil in accordance with said distances; a counter having an operating ratchet coaxial with said element; and a pawl carried by said rotary element and engaging said ratchet, to operate said ratchet 45 in one direction only.

4. In combination with a system of the class having a circuit which in practice is usually subjected to varying current increases immediately succeeded by a larger or smaller current increases or decreases; a magnet; a movable armature coil connected in said circuit and pivotally mounted in the field of said magnet, a gear sector 55 carried and oscillated by said coil, pawl controlled means operated by said sector, a register mechanism and means connecting said pawl controlled means and said register whereby said register may be actuated by movement of said coil in 60 accordance with the amount of each increase.

5. In combination, a system of the class having a circuit which in practice is usually subjected to varying current increases some immediately followed by an unequal current increases or decreases; a magnet; a movable armature coil connected in said circuit and pivotally mounted in the field of said magnet, a gear sector carried and oscillated by said coil, pawl controlled means operated by said sector and means, including a 70 registering mechanism connected to said pawl controlled means whereby to register the amount of each increase.

HERBERT KIENZLE.
